UNITED STATES PATENT OFFICE.

ROBERT SMITH, OF MIDDLETOWN, OHIO.

ELECTRIC HAMMER.

No. 881,482.

Specification of Letters Patent.

Patented Sept. 18, 1906.

Application filed August 8, 1905. Serial No. 273,239.

To all whom it may concern:

Be it known that I, ROBERT SMITH, a citizen of the United States, and a resident of Middletown, in the county of Butler and State of Ohio, have made certain new and useful Improvements in Electric Hammers, of which the following is a specification.

My invention is an improvement in electric hammers; and it consists in certain novel constructions and combinations of parts hereinafter described and claimed.

In the drawings, Figure 1 is a vertical longitudinal section of my improved hammer. Fig. 2 is a view, partly in section, at right angles to Fig. 1. Fig. 3 is a detail of the cap. Fig. 4 is a section on the line 4-4 of Fig. 1. Fig. 5 is a detail of the adjusting-screw. Fig. 6 is a vertical longitudinal section of a modified form.

In the present embodiment of my invention I provide a solenoid 1, comprising a section of brass tubing 2, threaded at each end and having screwed on either end thereof a fiber washer 3, 4, the wire being wound upon the tube between the washers, and a fiber sleeve 8 fitted over the wire between the washers for completing the insulating-case. The terminals of the solenoid are extended through the washers 4 and connected to the contact-points 5, 6, oppositely-disposed upon a second washer 7, also screwed upon the tube and provided with openings to permit the passage of the contact-points.

The solenoid is slidably mounted in a fiber sleeve 8, and surrounding the second sleeve and extending beyond the ends thereof is a metallic casing 9. A ring 10 is arranged within the casing above the solenoid and is provided with a diaphragm 11, having integral therewith a relatively short core 13, provided on its free end with a boss or projection 14, of phosphor-bronze or other suitable diamagnetic material, for a purpose to be hereinafter described. A pair of insulating-washers 15 are arranged in superposed relation centrally of the diaphragm and opposite to the core, being secured to the core by a set-screw 16 engaging perforations in the washers and a screw-threaded opening in the core. The set-screw is extended, as at 16^a, for a purpose to be described hereinafter, and between the washers are arranged oppositely-disposed spring-contacts 17, 18, comprising the transverse portion 17^a, adapted normally to engage the contact-points on the diaphragm, and the longitudinal portions 17^b, 18^b, adapt-

ed to remain in sliding contact with a pair of electrodes 19, 20, secured to a cap 21, fitting within the upper end of the tube, the electrodes being insulated from the cap in any suitable manner and connected at their outer ends to the terminal wires 22 of an electric circuit.

The casing 9 is provided with longitudinal slots 25, through which extend set-screws 24, 65 engaging screw-threaded openings in the ring 10. A similar arrangement is provided for the cap 21, comprising longitudinal slots 25 and the set-screws 26. By the above-described means both the cap and the ring are 70 permitted a slight longitudinal motion within the casing, but are retained from rotary motion therein, whereby the contact-springs 17, 18 are always maintained in proper alignment with the electrodes 19 and 20, a spring 27^x 75 being arranged between the cap and the ring to retain them in proper relation with each other.

The extended end 16^a of the set-screw 16 normally contacts with the set-screw 16^b, 80 traversing a screw-threaded opening in the cap 21, which is encircled between the cap and the set-screw 16 by a spiral spring 27, having its ends reduced to engage bosses 27^a 27^b on the set-screw 16 and the inner face of 85 the cap, respectively, a locking-screw 27^c engaging the outer end of the set-screw 16^b and the cap for locking the set-screw in its adjusted position.

A relatively long core 28 is arranged in the 90 lower end of the casing and comprises a section 28^a of relatively large diameter engaging the inner face of the casing and the core proper, 28^b, of relatively small diameter normally extending within the solenoid. 95

The outer end of the core is provided with an opening 29 for the reception of a tool, and a spring 30, arranged between the solenoid and the core, normally retains the solenoid in its upper position over the short core and with its contact-points in engagement with the spring-contacts.

A striking-ring 30^a, of phosphor-bronze, is arranged upon the lower end of the solenoid, a surface 31 being provided upon the portion 105 of the core of relatively large diameter for coacting therewith. The outer end of the core is reduced in diameter, and a collar 32 is secured to the inner face of the casing by set-screws 33 for limiting the outward motion of the core, a second collar 34 being secured to the core by set-screws 35 for limiting the in-

ward motion of the core. The collar 34 is set in such position that a slight amount of play is allowed to the core, and the spiral spring 30, arranged between the core and solenoid, 5 normally maintains the solenoid in contact with the short core and normally retains the long core in its outward position. For convenience in manipulating the tool a handle 37 is secured to the upper end thereof.

10 It will be evident from the description that the solenoid is maintained normally in its outward position and with the contact-points 5 and 6 in contact with the spring-contacts 17 and 18, whereby the circuit is completed. 15 The completion of the circuit through the solenoid tends to draw the core 28 farther into the solenoid; but since the core is fixed the solenoid is drawn over the core. The core 13 is carried with the solenoid until the boss or 20 projection 14 engages the end of the long core, which checks the movement of the short core and allows the solenoid to proceed alone until the striking-ring 30 engages the surface 31. As soon as the solenoid leaves 25 the short core, however, the circuit is interrupted, and the spiral spring 30 returns the solenoid to its original position. The diamagnetic boss 14 retains the two portions of the core out of direct contact with each other, 30 thus permitting the adjacent ends to retain their opposite polarity. The operation of the hammer is entirely automatic, since the movement of the solenoid completes and interrupts the circuit.

35 While I have described my invention as applied to an electric hammer, I do not choose to limit myself to this application, since it is evident that it may be made use of in any form of construction where a reciprocating motor is desired.

40 If desired, the striking-ring 30 may be replaced by a rubber ring, thus reducing the noise of operation, and for a like purpose the collar 32 might be faced with rubber.

45 It will be evident from the description that my invention is entirely automatic in its action and while simple in construction is yet efficient in operation and is not liable to easily get out of order.

50 While I have shown my invention as applied to a hammer, it is evident that it might with equal facility be used in any construction where a reciprocating motor would be desirable, as in pumps, brakes, trip-hammers, &c.

55 In Fig. 6 I have shown a modification wherein a solenoid A is arranged to act upon each end of a core B, the core being provided with arms C, extending through slots D in the 60 sides of the casing, by which the motor may be connected to a fixed part, while the arms E on the core are adapted to be attached to the part to be reciprocated. In the above construction the solenoids are coupled together

and act alternately, the construction of the 65 solenoids and connections being in all other respects similar to that shown in Fig. 1.

The provision of the slotted connection between the cap and the casing 9 allows the cup carrying the electrodes to slip out from the casing far enough to break the contact between the electrodes and the spring contact-fingers, so that by releasing the handle the circuit is broken. When the hammer is in use, the act of pushing the tool against the 75 work brings the electrodes and contact-fingers into contact to complete the circuit.

Having thus described my invention, what I claim as new, and desire to secure by Letters Patent, is—

1. In an electric hammer, the combination of a casing, an upper end cap slidably mounted within the casing, means for limiting the movement of the cap with respect to the casing, oppositely-disposed electrodes projecting through the cap and insulated therefrom, a solenoid slidably mounted within the casing below the cap, and provided with an insulating-casing, a diamagnetic ring secured to the lower end of the solenoid, contact-points connected with the terminals of the solenoid and projecting through the upper end of the insulating-case, a ring slidably mounted within the casing above the solenoid and provided with a diaphragm, a relatively short core integral with the diaphragm and coacting with the solenoid, contact-springs secured to the diaphragm and insulated therefrom, and adapted to complete the circuit between the electrodes and the contact-points on the solenoid, a second, relatively long core slidably mounted within the casing and coacting with the solenoid, means for limiting the movement of the core with respect to the casing, means whereby a tool may be attached to the outer end of the core, a spring for normally retaining the relatively short core at the upper end of the casing, a spring for normally retaining the solenoid and the relatively long core out of contact, means whereby the position of the ring may be adjusted with respect to the casing, a spring between the ring and the cap, and an electric circuit connected with the solenoid.

2. In an electric hammer, the combination 115 of the casing, a solenoid movably mounted within the casing, a relatively long core slidably mounted in one end of the casing, means for limiting the movement of the core, a relatively short core slidably mounted in the opposite end of the casing, means for limiting the movement thereof, a cap fitting within the upper end of the casing and provided with electrodes, spring-contacts secured to the core of relatively short diameter and insulated therefrom and adapted to make sliding contact with the electrodes, contact-points attached to the terminals of the solenoid and

adapted to contact with the spring-contacts when the core is in its upper position, a diamagnetic striking-ring on the lower end of the solenoid, a surface on the relatively long core for coacting with the striking-ring, a diamagnetic boss on the inner end of the short core and an electric circuit connected with the solenoid.

3. In apparatus of the class described, the combination of a casing, a solenoid slidably mounted within the casing, a diamagnetic striking-ring on the lower end of the solenoid, a relatively short core slidably mounted in one end of the casing and adapted to move with the solenoid, a relatively long core mounted in the lower end of the casing, and provided with a surface for coacting with the striking-ring, an electrical circuit connected to the solenoid, and means whereby the movement of the solenoid within the casing may make and break the circuit.

4. In apparatus of the class described, the combination of a casing, a solenoid movably mounted within the casing, a diamagnetic ring on the lower end thereof, a core mounted within the casing below the solenoid and provided with a surface for engaging the ring, an electric circuit connected with the solenoid, and means whereby the movement of the solenoid may make and break the current.

5. In apparatus of the class described, the combination of a casing, a solenoid movably mounted within the casing, a diamagnetic ring on the lower end of the solenoid, a relatively long core supported in the casing below the solenoid and fixed with relation thereto, a relatively short core supported above the solenoid and adapted to move therewith, means to restrain the movement of the short core with respect to the solenoid, a diamagnetic projection on the inner end of the short core and adapted to contact with the inner end of the short core, an electric circuit connected with the solenoid and means whereby the movement of the solenoid may complete and interrupt the circuit.

6. In combination a movable solenoid, an electric circuit connected therewith, a diamagnetic ring on one end of the solenoid, a relatively long fixed core having a surface for engaging the diamagnetic ring, a relatively short movable core, a diamagnetic projection on the inner end of one of the cores, means normally retaining the solenoid in position over the movable core, means whereby the passage of the current may actuate the solenoid to move over the fixed core, means for restraining the movement of the movable core with respect to the solenoid, means whereby the contact of the solenoid and short core may complete the circuit, and means whereby the separation of the solenoid and the movable core may interrupt the circuit.

65 7. In combination, a movable solenoid, an

electrical circuit connected therewith, a diamagnetic ring on one end of the solenoid, a relatively long fixed core having a surface for coacting with the ring, a relatively short movable core, a diamagnetic boss on the inner end of one of the cores for engaging the inner end of the other core, means for normally retaining the solenoid over the movable core, means for restraining the movement of the movable core with respect to the solenoid, and means whereby the contact of the solenoid and the movable core may complete the circuit and whereby their separation may interrupt the circuit.

8. In combination, a movable solenoid, an electric circuit connected therewith, a two-part core for the solenoid and of greater length than the solenoid, and comprising a relatively long fixed portion and a relatively short movable portion, a diamagnetic boss on the end of one of the portions for engaging the adjacent end of the other portion, means for normally retaining the portions separated, means for normally retaining the solenoid over the movable portion, and means whereby the contact of the movable portion and the solenoid may complete the circuit and whereby their separation may break the circuit.

9. In combination, a movable solenoid, a two-part core for coacting therewith, and comprising a relatively long fixed portion and a relatively short movable portion, diamagnetic means between the adjacent ends of the core whereby they may retain their opposite polarity, an electric circuit connected with the solenoid, means on the short portion of the core for engaging the solenoid to complete the circuit, means for normally retaining the solenoid in engagement therewith, means whereby the completion of the circuit may move the solenoid over the fixed portion and means to limit the motion of the movable portion with respect to the solenoid whereby the current is broken.

10. In combination a movable solenoid, an electric circuit connected therewith, a relatively short movable core for coacting with the solenoid, means on the core for engaging the solenoid to complete the circuit, means for normally retaining the solenoid in engagement with the core, means whereby the completion of the current may remove the solenoid from engagement with the core, and means for limiting the movement of the core with respect to the solenoid whereby the circuit is interrupted.

11. In combination, a movable solenoid, forming a part of an electric circuit, a two-part core of greater length than the solenoid for co-operating therewith, and comprising a relatively long portion and a relatively short portion, means for normally retaining the solenoid over the short core whereby the circuit is completed, and means whereby the

completion of the circuit may move the solenoid over the long core whereby the circuit is interrupted.

12. In combination a movable solenoid forming a part of an electric circuit, a two-part core of greater length than the solenoid for coöperating therewith, and comprising a relatively long portion and a relatively short portion, means whereby the movement of

the solenoid over the short core may complete the circuit, and means whereby the movement of the solenoid over the long core may interrupt the circuit.
